ATTORNEY

UNITED STATES PATENT OFFICE

HENRI LEON AUGUSTE FRANCOIS NOZIERES, OF PARIS, FRANCE

SIGNALING SYSTEM

Application filed September 11, 1924, Serial No. 737,022, and in France December 15, 1923.

My invention relates to electrical systems and particularly to electrical signaling systems in which electron tubes provided with two grids are employed. My invention also 5 relates to signaling methods.

One of the principal objects of my invention is the provision of an electric signaling system in which a large degree of amplification of received oscillations is realized.

10 Another important object of my invention is to provide four electrode thermionic devices provided with the usual anode, cathode and grid, a space-charge grid between the grid and cathode which has a high potential with respect to the cathode, the space-charge grid being connected to the anode supply 15 through an impedance, the usual grid being connected to the cathode through a second impedance which is coupled to the first impedance whereby an increase in amplification is secured and the space-charge in the 20 thermionic device is neutralized thereby increasing the rate of electron emission therein.

Other objects and advantages of my invention 25 will be apparent from the following description taken in connection with the accompanying drawing in which:

The single figure is a schematic diagram of a preferred embodiment of my invention.

30 Referring to the single figure, the electron device 1 comprises a cathode or filament 2, an anode or plate 5, a main grid element 4, and an auxiliary grid element 3 for partially or totally neutralizing the space charge 35 in the device. The filament 2 may be suitably heated from a source of power 6, the heating current being controlled by the variable rheostat 7.

The main grid filament circuit comprises 40 a coil 8 one end of which is connected to the main grid 4, the other end of which is connected to a suitable point on the potentiometer 18, which is connected across the source of power 6. The source of oscillation 17 is 45 connected across the coil 8 and a variable condenser 9 may be also connected across coil 8 for appropriately tuning the circuit to the oscillations.

The plate filament circuit comprises an oscillation responsive device 14, a coil 16 and a

source of power 13 all connected in series as shown. The auxiliary grid element 3 may be connected to any one of various taps brought out from the source of power 13 for varying the positive potential bias on the auxiliary grid element 3. 55

In the event that the auxiliary grid element 3 is not connected to the same tap from the source of power 13 as the plate element 5, a condenser 20 may be connected between 60 the said connections for bypassing high frequency oscillations. A variable condenser 19 may also be connected as shown for appropriately tuning its associated circuit to the oscillations. The coils 8, 15, and 16 are inductively coupled, the coupling between all or any two of said coils being adjustable from zero coupling to a comparatively large degree of coupling in either direction from zero coupling. 70

If the space charge in an electron device is totally or partially neutralized, the passage of electrons from the cathode to the anode is greatly accelerated, thereby resulting in the requirement of a comparatively 75 small source of plate or anode potential for a given value of plate or anode current. In the system described above, this space charge is totally or partially neutralized by means of the auxiliary grid element 3 which 80 has a positive potential bias imparted to it from the source of power 13. Due to the fact that the various coils 8, 15, and 16 are inductively and variably coupled, regeneration can be effected resulting in a comparatively 85 large degree of amplification of the oscillation impressed on the system. The auto-dyne reception, detection, and amplification of oscillations is also made possible by the above described system. 90

Satisfactory reception, detection and amplification of oscillations may be also realized by the above described system when the source of power 13 is dispensed with.

In the case where the arrangement comprises several stages of amplification, additional inductive couplings could be provided between the different stages for controlling the degree of amplification. 95

While I have shown and described a pre- 100

ferred embodiment of my invention I do not limit myself to the same but may employ such other modifications as come within the spirit and scope of my invention.

5 I claim:

- 10 1. The combination with a thermionic device having the usual input electrodes connected externally of the device through an impedance and a plate electrode, of an auxiliary grid interposed between the input electrodes and suitably biased through a second impedance from the plate supply for neutralizing the space charge in said device thereby increasing the rate of electron emission therein, both said impedances being coupled.
- 15 2. In combination in a space discharge device provided with a cathode, anode and control electrode and having its input and output circuits inductively coupled, of a fourth electrode interposed between the input electrodes forming the input circuit and connected through an inductance to the plate source, said inductance being coupled to both input and output circuits.
- 20 3. The combination with an electron discharge device having the usual cathode, grid and plate electrodes, of an input circuit connected between said cathode and grid electrodes, an auxiliary grid electrode interposed between said cathode and grid, an output circuit including a source of high potential connected between the plate and cathode, a third circuit connected between the auxiliary grid and the source of high potential and means for variably and inductively coupling said mentioned circuits.
- 25 4. A circuit arrangement comprising a vacuum tube having a main grid and an auxiliary grid, an input circuit including said main grid, an output circuit including a source of high potential, an auxiliary grid circuit connected between said source of potential and the auxiliary grid, and an inductance in each of said mentioned circuits coupled to one another for providing a variable coupling between the circuits.
- 30 5. A circuit arrangement comprising a vacuum tube having a main grid and an auxiliary grid, a cathode and an anode, a source of high potential for said anode, an input circuit connected between said main grid and cathode, an output circuit including the source of potential connected between anode and cathode, and a connection through an inductance between the auxiliary grid and said source of potential for positively biasing said grid, and means for variably coupling said inductance externally to both said input and output circuits.
- 35 6. In combination, a four electrode thermionic device provided with the usual anode, cathode and grid, a space-charge grid between the usual grid and cathode, the space-charge grid having a high potential with re-

spect to the cathode and being connected to the anode supply through an impedance, the usual grid being connected to the cathode through a second impedance which is coupled to the first impedance.
